DESIGN FOR A PENDANT

Frank A. Blasi, Newark, N. J.

Application August 4, 1937, Serial No. 70,846

Term of patent 3½ years

To all whom it may concern:

Be it known that I, Frank A. Blasi, a citizen of the United States, whose post-office address is Nos. 31-33 Governor Street, in the city of Newark, county of Essex, and State of New Jersey, have invented a new, original, and ornamental Design for a Pendant, of which the following is a specification, reference being had to the accompanying drawing, forming part thereof.

My design is characterized by a cross having integrally formed therewith a miniature rosary as shown.

I claim:

The ornamental design for a pendant, substantially as shown and described.

FRANK A. BLASI.
